UNITED STATES PATENT OFFICE

141,385

DESIGN FOR A MERCHANTISE DISPLAY CABINET

John Romadka, Wauwatosa, Wis., assignor to Robert A. Johnston Company, Milwaukee, Wis.,
a corporation of Wisconsin

Application December 4, 1944, Serial No. 116,696

Term of patent 14 years

(Cl. D80—11)

To all whom it may concern:

Be it known that I, John Romadka, a citizen of the United States, residing at Wauwatosa, in the county of Milwaukee and State of Wisconsin, have invented a new, original, and ornamental Design for Merchandise Display Cabinet, of which the following is a specification, reference being had to the accompanying drawing, forming part thereof.

Figure 1 is a perspective view of the front and one end portion of the display cabinet showing my new design; and

I claim:

The ornamental design for a merchandise display cabinet, as shown.

JOHN ROMADKA.
